UNITED STATES PATENT OFFICE.

HENRY A. TOBEY, OF DAYTON, OHIO.

AIR-FLUE REGISTER.

SPECIFICATION forming part of Letters Patent No. 257,107, dated April 25, 1882.

Application filed February 24, 1882. (No model.)

To all whom it may concern:

Be it known that I, HENRY A. TOBEY, of Dayton, in the county of Montgomery and State of Ohio, have invented certain new and useful Improvements in Air-Flue Registers, of which the following is a full, clear, and exact description.

Reference is to be had to the accompanying drawings, forming part of this specification, in which similar letters of reference indicate corresponding parts in both the figures.

Figure 1 is a perspective view of one of my improved registers, the grate-door being shown detached. Fig. 2 is a sectional side elevation of the same, the grate-door being shown in place.

The object of this invention is to prevent liquid and solid filth thrown into the register from entering the flue, and also to facilitate the cleansing of the register.

The invention consists in an air-flue register constructed with an inclined bottom having its inner part curved upward and forward to prevent any liquid or solid from passing from the said bottom into the air-flue, a back formed of cross-slats arranged with each lower slat a little in the rear of and at a less inclination than the next upper slat, to prevent any liquid filth thrown into the register from entering the air-flue, and with a removable grate-door provided with a lock, whereby the register can be readily cleaned; also, in the combination, with the register-walls having sockets, of a removable grate-door having lugs and a lock, whereby the grate-door can be readily removed and the register cleansed; and also in the combination, with the inclined bottom of the grate-door provided with notches in its lower edge, as will be hereinafter fully described.

A represents the register, the side walls of which are vertical and the top wall horizontal. The bottom B of the register inclines upward from its forward edge, so that any fluid thrown into the register will flow out at the front of the said register. The rear part of the bottom B is curved upward and forward to such a point that a vertical line drawn through the upper edge of the said curved part will fall within the said curve, so that a fluid thrown against

the rear part of the said bottom will not flow into the air-flue, but will be guided forward by the said rear part and will fall back into the register.

The inner side or back of the register is formed of slats C, the ends of which are cast in or otherwise securely connected with the side walls of the register, and the upper edge of the upper slat is formed solid with or is closely connected to the rear edge of the top wall of the said register. Each upper slat is set farther forward than the preceding one and at a greater inclination, as shown in Fig. 2, so that any liquid thrown into the register and that comes in contact with and flows up the said slats will drop from the upper edge of each upper slat upon the inner side of the next lower slat, and thus flow back into the register. The slats C overlap each other, and are placed at such a distance apart that the fingers can be inserted between the slats for convenience in washing the said slats when required. With this construction it will be impossible for liquid or solid filth thrown or pushed into the register to get into the air-flue.

The register is secured in place by screws passing through holes D in the side walls of the register and into timbers built in the wall of the room, so that the register cannot be worked loose and taken out when the grate-door E is in place. The side flanges, F, of the front of the register have rearwardly-projecting flanges G upon their outer edges to prevent the occupants of the room from forcing anything beneath the said flanges F, and thus prying the register loose.

The front of the register is closed by a grate, E, which has lugs I formed upon one edge to enter sockets J, formed in the side walls of the register. The grate E is secured in place by a lock, K, the bolt of which shoots into a socket, L, formed in the side wall of the register A. The lock K should be so made that it cannot be picked by the occupants of the room, and should be made in skeleton form, so that it can be readily cleansed.

In the lower edge of the grate-door E are formed notches M, as shown in Fig. 1, to allow liquid filth that may be thrown into the reg-

ister to flow out freely. With this construction the register can be readily opened and cleansed when necessary.

My improvement is especially designed for 5 insane asylums, prisons, and infirmaries, but can be used with advantage in other places.

Having thus fully described my invention, I claim as new and desire to secure by Letters Patent—

- 10 1. An air-flue register constructed, substantially as herein shown and described, with an inclined bottom having its inner part curved upward and forward, a slotted back, and a removable grate-door provided with a lock, as 15 set forth.
2. In an air-flue register, the back formed of inclined overlapping cross-slats C, arranged with each lower slat a little in the rear of and at a less inclination from the perpendicular 20 than the next upper slat, substantially as herein shown and described, whereby liquid filth thrown into the register is prevented from entering the air-flue, as set forth.

3. In an air-flue register, the bottom B, having a slight upward inclination, and having its 25 rear part curved upward and forward, substantially as herein shown and described, whereby liquids and solids are prevented from passing from the said bottom into the air-flue, as set forth.

30 4. In an air-flue register, the combination, with the register-walls having sockets J and L, of the removable grate-door E, having lugs I and a lock, K, substantially as herein shown and described, whereby the grate-door can be 35 readily removed and the register cleansed, as set forth.

5. In an air-flue register, the combination, with the inclined bottom B, of the grate-door E, provided with the notches M in its bottom 40 edge, substantially as and for the purpose set forth.

HENRY A. TOBEY.
